UNITED STATES PATENT OFFICE.

JOSEPH F. POND, OF CLEVELAND, OHIO.

GAS-STOVE.

SPECIFICATION forming part of Letters Patent No. 358,478, dated March 1, 1887.

Application filed October 23, 1885. Serial No. 180,746. (No model.)

To all whom it may concern:

Be it known that I, JOSEPH F. POND, a citizen of the United States, residing at Cleveland, in the county of Cuyahoga and State of Ohio, have invented certain new and useful Improvements in Gas-Stoves; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to gas-stoves for heating and cooking purposes, and the novelty consists in the construction, arrangement, and adaptation of parts, as will be more fully hereinafter set forth, and specifically pointed out in the claims.

I provide for feeding air to the volume of gas before it reaches the burner, and for peculiarly distributing the mixed air and gas before it reaches the jets. I provide a water-vessel between the series of jets, and means for attracting such water to points adjacent to the jets, where it is formed into steam and consumed to intensify the combustion. The water thus used serves to keep the burner cool. I form the gas conductor and mixer in sections, and provide that when said sections are secured together they shall clamp between them a peculiar nozzle, which shall be nearly surrounded by air-inlet spaces. I provide an air-inlet, or more than one of such inlets, between the nozzle and the burner, and I so construct the nozzle that the volume of gas will be deflected from the region of the air-inlets, to insure a vacuum or vacuums at such points and to insure the ingress of air without any egress of gas. I provide a spider-support the arms of which serve as means for conveying the water from the central reservoir to the region of the jets by capillary attraction. These and other features of novelty and importance are fully illustrated in the accompanying drawings, which form a part of this specification, and in which—

Figure 1 is a vertical central section. Fig. 2 is a detail elevation of the water-cup and gas-distributer. Fig. 3 is a detail elevation of the spider-support. Fig. 4 is a top plan

view, on a smaller scale, with cup and spider removed. Fig. 5 is an end elevation of the two-part conductor and mixer, with the gas-jet clamped between.

Referring to the drawings, A designates a body having leg-supports A', and A² designates a bowl-shaped body, preferably cast in one piece with the body A and legs A', and having a depending open neck, A⁴, which connects with a gas conductor and mixer, C. The conductor C is formed of two parts, C' and C², which together form a flaring-mouthed tube, D. The part C', by a post and screw, d, is secured to the body A, and by a screw, d', is secured to the neck A⁴ of the bowl A², while a horizontal screw or bolt, d², secures the parts C' C² together.

Upon the inner surface of the flaring mouth 70 of the tube D are arranged two opposite pairs of guides, those upon the part C² being shown in Fig. 5 at c, and those upon the part C' being shown at c'. These guides c c' receive and embrace the arms f² of the gas-nozzle F, and 75 said nozzle is securely clamped between the parts C' C², as said parts are held together by the screw or bolt d².

The nozzle F has a threaded portion, f', which engages a similar part of a gas-coupling, G, having a valve, g, and it is arranged centrally, or nearly so, with the walls of the flaring mouth of the tube D. The nozzle is, however, of such smaller dimensions than the tube as to leave air-inlet spaces d² between it 85 and the mouth of said tube. By a hollow bulge, D', formed partly by each of the parts C' and C², I provide an air-inlet chamber between the nozzle F and the bowl A², to which, upon either side, is an open-air connection, d'. 90

H designates a water-reservoir with closed bottom. It is made of contour to correspond with the bowl A², but of such smaller dimensions as to leave between the two an annular chamber, H', through which the mixed air and 95 gas arises to the burning jets. Formed upon the outer surface of the cup H are a series of equidistant vertical ribs, h, which extend to or near the inner surface of the bowl A², and these ribs serve to take up and evenly distribute the 100 gaseous fuel to the jets h' above. These jets h' are flaring downward and are so arranged as to project the flames inward, while the cup H is supported on nibs or shoulders i to support

the outer flange of the cup slightly above the upper edge of the bowl, leaving a space, i' , through which the gaseous fuel passes in a sheet.

5 K designates a removable spider having a point, k' , which is stepped into a central socket, h^2 , in the bottom of the interior of the cup H, and having equidistant arms k of shape corresponding with the inner contour of the said cup H and lying closely adjacent thereto. Each arm k has a vertical projection, k^2 , which serves as a support for any convenient vessel over the burner, and an arm, k^3 , which projects outwardly and rests upon the upper flange 15 of the cup H.

To provide further facilities for cooking, I furnish a circular plate, B, with open center, through which the burner operates, and it has two concentric upwardly-extending annular flanges, b , between which is formed an annular receptacle, b' , which serves conveniently to catch any matter that spills or boils over from the culinary vessel in use. This plate has perforated nibs or ears b^2 , by means of which and 20 of screws b^3 it is conveniently secured removably to the casting A.

The gas-passage f in the nozzle F is deflected downwardly, and this position serves a peculiar and double function, namely: first, to direct the stream of gas distant from the air-inlet d^4 , and, second, to impinge it against the bottom of the tube D and against its back vertical wall in such a manner that it will eddy and reverberate and become thoroughly mixed 35 with the air before it reaches the distributor or passes to the burning jets.

An annular casting, M, rests upon the plate B, between its flanges b , and it has vertical arms m , which serve to support a culinary 40 vessel.

The operation and advantages of the device may be briefly stated as follows: The valved coupling G may be connected with any source of gas-supply, preferably flexible. The gas 45 passing through the nozzle F creates a partial vacuum in the mouth of the tube D, which draws in a quantity of air through the inlets d^5 . The stream of gas is directed against the bottom of said tube to create a partial vacuum 50 in the chamber formed by the walls or bulge D', and this further draws in air through the ports d^6 . The gas and air are impinged against the vertical wall of the tube D and become intimately mixed before the flow reaches the 55 neck A' of the bowl A². As the mixed gas and air pass upward they are evenly distributed between the burning jets by the arms h , and the fuel passes upward between the bowl A² and the cup H, a portion passing out in a 60 thin sheet between these parts and another portion being deflected inwardly through the flaring jets h' . The cup H having been more or less filled with water, the arms k of the spider K act by the law of capillary attraction 65 to carry the water in small quantities up to the heated portions of the burner, adjacent to the flames, but inside the sheet-flame, where

it is converted into steam. As the sheet-flame curls over the edge of the cup H inwardly from all points, the rising steam can only escape by passing through this flame, where it is consumed to increase the heat of the flame. The body of water in the cup at the same time 70 serves to prevent undue heating of the parts and insures that the sheet of fuel shall reach the burners in a comparatively cool state, in which condition it has the greatest advantages.

Modifications in details of construction may be made within wide limits without departing from the principle or sacrificing the advantages 80 of the invention.

In some conditions the air-inlets d^5 may be sufficient, and those d^6 may be dispensed with.

The construction by which air-spaces are left 85 between drip-receptacle A' and burner-body A is claimed and shown in a separate application, No. 184,706, filed December 4, 1885.

What I claim as new is—

1. In combination with a circular burner, a centrally-arranged water-reservoir having its 90 walls formed in part of the structure of the burner, the body of water in the reservoir serving to prevent undue heating of the burner, and the vapor of water as it rises being impinged upon the flame to augment the same, 95 as set forth.

2. In a gas-stove, a circular burner having its inner wall formed into a water-holding reservoir, as set forth.

3. The combination, with a circular burner 100 formed in part of a water-holding reservoir, as described, of a vessel-supporting spider having its arms extending from the interior of the reservoir to points above the top of the same, as and for the purposes set forth.

4. The combination, with a bowl, as A², and gas-connections, of a removable water-reservoir forming one wall of the gas-passage, and the whole arranged to serve jointly, as set forth.

5. The combination, with a bowl, as A², and gas-connections, of a removable water-cup forming one wall of the gas-passage and having distributing-arms, as h , as and for the purposes set forth.

6. The combination, with the bowl A², having nibs i and gas-connections from below, of the removable cup H, having flaring jets h' and forming one wall of the gas-passage, the said cup being supported upon said nibs i , to leave thin gas-spaces between the bowl and cup additional to said flaring jets, as and for the purposes specified.

7. In a gas-stove, substantially as described, the plate B, having concentric flanges b , to form drip-receptacle b' , combined with the body A 125 and with the burner A² H, as and for the purposes set forth.

8. The combination, with the plate B, having drip-receptacle b' , and with the burner arranged as shown, of the support M m , of circular form, and supported upon the plate, for the purpose set forth.

9. The combination, with the bowl A and removable water-cup having jets h' and step h^2 , of

the spider K, having point k' and arms k , with projections k^2 and k^3 , and means for supplying gas, as and for the purposes set forth.

10. In a gas-stove, substantially as described, 5 the combination, with a gas-feeding nozzle, of a fuel-conductor, as D, formed in two parts, and securing means, as d^2 , the said nozzle being clamped between the two parts of the conductor when the said means d^2 is adjusted, as to set forth.

11. In a gas-stove, the two-part conductor comprising the parts C C', secured together by means which clamp the nozzle F between them, said nozzle being smaller than the interior 15 space between said parts C C', to leave air-spaces d^3 between the conductor and nozzle when thus secured, combined with said nozzle and securing means, as set forth.

12. In a gas-stove, the combination, with the

two-part conductor C C', having flaring mouth 20 and nibs or guides $c c'$, of the gas-nozzle F and the securing screw d^2 , as and for the purposes specified.

13. The combination, with the conductor D, having a vertical wall which leads to the burner 25 and distributing device, and having air-inlets, as d^4 , of the nozzle F, having gas-passage f , deflected from such inlets and in the direction of the lower wall of the conductor, whereby the gas and air will be intimately mixed before 30 reaching the distributers, as set forth.

In testimony whereof I affix my signature in presence of two witnesses.

JOSEPH F. POND.
